UNITED STATES PATENT OFFICE

MARTIN D. ZIMMERMAN, OF WASHINGTON, DISTRICT OF COLUMBIA, AND HARRY PULLEN, OF PRESTON, MARYLAND, ASSIGNEES TO INTERNATIONAL PATENTS CORPORATION, OF REHOBOTH BEACH, DELAWARE, A CORPORATION OF DELAWARE

MUSICAL INSTRUMENT

Application filed March 22, 1930. Serial No. 438,125.

Our invention relates to new and useful improvements in musical instruments, and has for an object to produce an instrument that may be readily played by anyone, it necessitating simply the turning of a handle while air is blown into or drawn from the instrument.

Still another object of the invention is to provide a musical instrument in which there is placed a harmonica over which is drawn the paper from a music roll and the harmonica being so arranged that the air will be fed into a cylinder enclosing the harmonica and the air thus directed to the harmonica from its opposite ends.

Still another object of the invention is to provide a musical instrument in which there is fitted a unit, which unit comprises a hollow cylinder closed at its ends. There is a harmonica tightly fitted within the cylinder while a bifurcated passageway for the air extends to the opposite ends of the closed cylinder.

Still another object of the invention is to provide a musical instrument comprising a cylinder closed at its opposite ends, in which there is fitted a harmonica, there being a passageway for the air in the opposite ends of the cylinders and there being a form of baffle plate near the opposite ends of the cylinders, so that it is impossible to suddenly blow the paper music sheet away from the said harmonica, and so that the air will be more evenly distributed to the various reeds.

Still another object of the invention is to provide a musical instrument in which there is fitted a cylinder closed at its opposite ends and in which cylinder there is a harmonica, and wherein the casing of the musical instrument forms a sonorous body or sound box, so that the music emitted will have intensity as well as timbre or quality.

Still another object of the invention is to produce a musical instrument in the form of a casing with a curved top, so that the casing, in turn, forms a resonant chamber, there being a plurality of openings around the edges of the lid of the casing while cup-shaped pieces or bells are also secured in the front edge of the casing to further cause the music

to be rich in tone and also be of good quality or color.

Still another object of the invention is to provide a musical instrument, the casing of which is formed to lend quality to the music, the casing, in turn, being provided with an arrangement for receiving and operating a music roll which is passed over a reed instrument or harmonica, means also being provided for admitting the air around the sides and lower portion of the harmonica and forcing the same up and through the mouth of the harmonica.

Still another object of the invention is to provide a musical instrument provided with a casing of such construction as to lend timbre or quality to the instrument and to provide a unit which may be easily placed within the casing, which unit comprises a harmonica, means for feeding air evenly to the same, and a still further unit which comprises the music roll and the means for turning the same.

With these and other objects in view, the invention consists in certain new and novel arrangements and combination of parts, as will be hereinafter more fully described and pointed out in the claims.

Referring now to the drawings showing a preferred embodiment of our invention,

Fig. 1 is a top plan view of our improved musical instrument, a portion being broken away to show how the mouth-piece is screwed into place;

Fig. 2 is a side elevation of the same;

Fig. 3 is a plan view of the instrument with the lid thrown back and parts broken away for the sake of clearness;

Fig. 4 is a sectional view taken on the line 4-4 of Fig. 3;

Fig. 5 is an enlarged sectional view on the line 5-5 of Fig. 3, with the lid closed;

Fig. 6 is a detail view of what we term the musical unit;

Fig. 7 is a perspective of one of the music roll spools.

Casing

Referring now more specifically to the drawings, there will be seen a rectangular

casing 1, which is preferably made of metal, for sake of cheapness of manufacture, although other desirable materials might be used. The sides 2 of the casing are substantially triangular in shape and have their highest point at the centers 3, as may be seen in the several views. There may also be seen a lid 4 which is hinged at its rear, as at 4', and this lid 4 has the downwardly projecting rims at each of its sides, so that the lid itself adds vertical dimension to the casing as a whole. It will be noticed that the rims 5 of the lid are provided with a plurality of openings 6, which may vary in size, as we have found that even with the openings at the front of the lid, which will be shortly explained, it is necessary to provide additional openings around the sides of the lid to produce clear musical notes.

Along the front edge of the casing 1, there may be seen the three small bells 7 which are carried by the front edge of the casing, and the lid, will be provided with small cut-away portions 8 to properly encircle the inner ends of the bells, so that the lid may be tightly closed.

In Fig. 1, it will also be noticed that the lid near its front edge is provided with the elongated slots 9, so that the musical sounds may be emitted through the opening 6 around the lid, the bells 7 along the front of the instrument, and the elongated slots 9 along the front upper edge of the lid. With these various and multiplicity of openings, the musical tones are emitted from the instrument rich in tone and of good intensity. Thus, it will be seen that by providing the casing with the upwardly sloping sides and a relatively high lid, the entire casing forms a good sound box or sonorous body to thereby give strength or amplitude and quality or color to the musical tones.

Instrument unit

Referring now to the instrument unit, it will be seen that the same comprises a cylinder 10 which is preferably made of a thin metal and has its two ends sealed by the respective plates 11. Before sealing this tube or cylinder, however, a mouth organ or harmonica 12 is placed within the cylinder 10 and has its upper edge or mouth tightly fitted within the rectangular slot 13, that is cut in the cylinder near its top.

Referring for the moment to Fig. 5 where this harmonica 12 may be seen in section, it will be noticed that a small gasket 14, which may be of rubber or cork, is secured around the upper outer edge of the harmonica and rests against the shoulders 15 of the outer side plates 16 of the harmonica. Thus, it will be seen that when the harmonica 12 is fitted up within the slot 13, this cork or rubber gasket will abut against the inner surface 65 of the cylinder about the slot and tightly seal

the upper edge of the harmonica with relation to the tube or cylinder. This must be so, as the air is to be fed at the opposite ends of the cylinder or tube, as will be shortly explained.

Referring a moment to the harmonica 12, there may be seen in Fig. 5 that it consists of the center board 17 which has the regular slots therein so that the reed plates with the reeds 18 will be located opposite the slots in the usual manner and will be set in vibration by the air impinging against them.

The harmonica, however, has additional little rubber coverings or flaps 19 for each reed slot, one being placed on the inner side of the slot in front of the reed, while the oppositely located reed will have the small rubber flap over the outside of its slot, so that if air is blown through the harmonica from the bottom and out through the mouth of the harmonica and a note is to be played, the particular reed in question will vibrate because the rubber flap will be blown away from the opening behind the reed, whereas if the air is drawn through the mouth of the harmonica, the rubber flap just referred to will close the opening, and the cooperating opposite reed will come into function, as its rubber flap will be drawn away from its respective slot rather than forced against it.

This is necessarily so, as the air is to be blown into the instrument or drawn through the instrument and the perforated music roll in passing over the mouth of the harmonica and the various openings selects a certain note, or notes, to be played and this must be played whether the air happened to be going into the harmonica or was being drawn through it.

After the harmonica has been placed within the tube or cylinder, small wedges 20 are driven in from the opposite ends of the cylinder 10 to tightly hold the harmonica in position in its slot and to jam the heretofore-mentioned gasket up against the walls and cylinder.

There may also be seen in Figs. 3 and 4 the small baffle plates 21, which have the series of perforations 22 and which may be held against the opposite ends of the harmonica by the respective screws 23.

It will be noted that these baffle plates are slightly spaced from the respective end plates 11 to form the small chambers 24, while from these respective chambers there are the passageways or openings 25 which are connected by the pipe 26, which has the two respective branches, these branches being secured at 27 to the cylinder 10 over the opening 25. There is a common inlet 28 for this pipe 26 so that when the air enters the inlet 28 it will be divided and directed to the oppositely located chambers 24, as will be readily understood.

To conveniently fit the lips, there is shown

70

the mouth-piece 29 which is threaded within the inlet 28. It might also be mentioned here that this inlet 28 is passed through the rear of the casing and if, for any reason, it is desired to remove the unit, the mouth-piece 29 will be first unscrewed, after which small holding screws 30 may be removed which, it will be seen, pass through the sides of the casing and fit within the end plates 11 of the tube or cylinder 10.

As far as this unit has been described, it will be seen that air entering in the mouth-piece 29 will be evenly distributed to the opposite chambers 23 and there baffled by the small plate 22 to thus be evenly distributed throughout the length of the cylinder to the harmonica.

We have found this a great advantage over other musical instruments of this general type, as not only will it prevent the paper of the music roll, about to be described, from being blown away from the mouth of the harmonica should the player suddenly blow a hard breath into the unit, but it will produce a more evenly distributed volume of air and thus more effectively and evenly operates the reeds to in turn produce more evenly sounded notes.

Of course, should the perforated music strip be blown away from the mouth of the harmonica, not only will more wind be necessary to operate the instrument but false notes might be played.

It will also be seen that should the harmonica in any way become damaged or any of the reeds become affected, it is a relatively simple matter to remove the above-mentioned unit, insert a new harmonica and replace the unit.

As may be seen in Fig. 5, there is a small drain plug 31 which leads into the bottom of the cylinder 10 so that should the moisture or saliva collect in the cylinder, it may be drained when desired.

It will also be noticed from Figs. 4, 5 and 6 that the harmonica is not positioned vertically within the cylinder 10, but is positioned slightly angularly to a vertical line, while in the same manner the slot 13 is not formed in the center of the top of the tube but at a slight distance from the top, so that the perforated paper roll 32 will more tightly hug or cover the slot than if this arrangement were not followed out.

Also, as may be seen in Figs. 1 and 3, there is a window 33 cut in the lid of the casing, so that the player may see the perforations in the music roll and then accentuate or slow down the action of the music roll at certain times, similar to the way automatic piano players are operated.

The sounds will pass out through the mouth of the organ and strike the lid and be deflected and, in turn, set the entire casing in vibration. Of course, there will be a cer-

tain amount of vibration of the tube or cylinder 10 to also effect the vibration of the casing or sonorous body, and there is thus produced a surprisingly loud and rich tone, far different from musical instruments of this general type that are more or less but toys.

Music roll

Having thus described the casing and the musical instrument, a short description of the means for holding the music roll and its operation will be set forth.

However, it is not thought necessary to describe the perforated music roll itself, as it is similar in all respects to the perforated roll used in player pianos but, of course, on a much smaller scale.

Referring to Fig. 3 for the moment, there will be noticed the operating handle 34 which is suitably mounted at one side of the casing on the small stud shaft 35 which will fit within one end of the blank spool 36.

In Fig. 7, there will be seen the spool in detail, it consisting of the little circular end pieces 38, central shaft or hub 39, which is cut out, as at 40, while extending over this cut-out portion and slightly spaced from the bottom thereof, may be seen the rod 41 so that the beginning of the paper roll may be quickly and readily threaded about the spool.

To engage and support the other end of the spool 36, we provide a little stub shaft 42 at the opposite side of the casing, which shaft fits within the collar 43. This stub shaft 42 has the end piece 44 near its end so that a spring 45 may be placed between the adjacent wall of the casing and this end piece to normally hold the end piece tightly against the end 38 of the spool.

There also will be noticed the little pin 46 that fits within the slot 47 of the collar 43 so that when first placing the spool 36 in position the same may be moved slightly laterally, after which the other end of the spool will have fitted therein the little stub shaft 35 on which the handle 34 is located. After the spool has been once fitted, a little pin 35' may be fitted through the shaft 35 and the spool shaft 39 so that the spool is kept in proper position.

There will also be noticed the little rewind handle 48 on the stub shaft 49, which shaft will engage one end of the spool 50 on which is wound the perforated music sheet 32, while adjacent the opposite end of this spool will be the little supporting shaft 51 with its collar 52, the spring 53 and the other little parts similar to the little shaft 42 and its associated parts, just described, although this spool 50 will have slightly more lateral movement so as to disengage the spool from the inner end of the shaft 49 in order to remove the roll just played and insert a new one.

It might also be mentioned that the spring 53 and its cooperating parts act as a brake

for the winding of the music roll, so that when the little handle 34 is turned, there will be sufficient tension on the roll to wind the same up evenly and tightly. In the same manner, when the handle 48 is used to rewind the roll, the spring 45 will act as a brake and the music sheet will be rewound tightly and easily to its original position.

The two spools are so located that there will also be some little friction as the paper passes over the cylinder and tracks over the mouth of the harmonica, thus keeping the paper tight at all times to prevent the escape of air between the mouth of the harmonica and the paper.

It will also be noticed that we thread the music roll under the winding spool rather than over the top, so that as it feeds from the top of one spool it will pass over the mouth of the harmonica and then down under the winding spool.

From the above description, it will be readily apparent that a music roll may be quickly and readily placed in position and then quickly threaded to the blank spool after which the little handle may be turned and the music will track and be tightly held against the mouth of the musical instrument or harmonica that lies flush with the outer surface of the casing or tube that holds the harmonica.

It will also be seen that the music roll may be quickly rewound to its original position and either played over again or a new music roll inserted. It is also to be understood that although we have shown a harmonica of sixteen notes, the parts may be enlarged and built to accommodate a thirty-two note instrument.

Conclusion

From the foregoing, it will be seen that we have produced a musical instrument that is exceedingly simple to play, but wherein after the player has familiarized himself with the same, he can, in time, produce better music than a beginner, similar to the manner in which a player-piano may be operated with different degrees of skill.

It will also be seen that by producing a musical instrument wherein the casing acts as a sound box, richer and more colorful music may be produced than on instruments of the same general type that do not have this feature. Furthermore, it will be seen that most of the air is blown into the cylinder and passes out through the mouth of the organ, rather than having the air pass directly through the mouth of the organ and then out of the instrument. This latter only happens when the breath is drawn in by the player, which takes place intermittently and for periods of short duration. Furthermore, by sealing the two ends and providing the baffle plates, the air is more evenly fed and

distributed to the harmonica than has heretofore been the case.

Finally, by providing the casing as shown with the various sound openings and by shaping the casing so that the same may act as a sound box, the musical tones will be rich and of pleasing intensity.

Many slight changes might be made without in any way departing from the spirit and scope of the invention.

Having thus described our invention, what we claim as new and desire to secure by Letters Patent is:

1. In a musical instrument, a casing in the form of a sound box, means within the same for enclosing a harmonica, means for supporting rollers within the casing, and means for delivering air to the opposite ends of the means enclosing the harmonica.

2. In a musical instrument, a casing in the form of a sonorous body, sealed means within the same for holding a harmonica, means for supporting rollers within the casing to carry a perforated music roll across the mouth of the harmonica, and means for delivering air to the opposite ends of the sealed means that encloses the harmonica.

3. In a musical instrument, a casing in the form of a sound box, sealed means within the same for holding a harmonica, a harmonica within the sealed means and having its mouth extending without the sealed means, means for supporting rollers within the casing to carry a perforated music roll across the mouth of the harmonica, and bifurcated means for delivering air to the sealed means to thereby operate said harmonica.

4. In a musical instrument, a casing in the form of a sound box, a harmonica in the casing, means within the casing enclosing and sealing all but the mouth of the harmonica, means for restrictively feeding air to the enclosing means so that air will pass up from the bottom of the harmonica and out through the mouth of the same, and means for selecting the notes of the harmonica to be operated.

5. In a musical instrument, a casing in the form of an amplifying chamber, a member within the casing sealed at its both ends and having a slot in the upper portion thereof, a harmonica within the sealed member and having its mouth extending in said slot, means for supplying air to the opposite ends of the member and passing out through the mouth of the harmonica, and means for passing a perforated music roll over the mouth of the harmonica.

6. In a musical instrument, a casing in the form of a sound box, a member within the casing and sealed at its opposite ends, said member provided with an elongated slot, a harmonica having its mouth fitting up with in the slot, means for directing the air to

both ends of said member, means for passing a perforated music roll over said slot whereby air may be directed to the opposite ends of the chamber and into the harmonica and out the mouth thereof and also drawn in through the mouth of the harmonica and out of said chamber.

5 7. In a musical instrument of a player type, a sound box, a sealed unit within said sound box, a harmonica in said unit and having its mouth extending without the unit, means for feeding air to the sealed unit, means within the sealed unit for baffling the air fed thereto and means for passing a perforated music sheet over the said unit and mouth of the harmonica.

8. A musical instrument comprising a casing, a musical unit within the casing, said unit comprising a tubular member sealed at its ends, a harmonica within the member and the mouth thereof extending without the member, means for feeding air to the opposite ends of the member, means for baffling the air before passing through the said harmonica, and means for passing a music roll over the mouth of said harmonica.

9. A replaceable unit for a musical instrument including a hollow member sealed at its ends and provided with an elongated slot on its upper surface, a harmonica within the member and having its mouth fitting and sealed within said slot, and means for feeding air into the hollow member.

10. A unit for a musical instrument comprising a hollow member sealed at its ends and provided with an elongated slot, a harmonica within the member and having its mouth sealed within the slot, and a bifurcated passageway for feeding air into the hollow member.

11. A unit for a player type of musical instrument comprising a hollow member sealed at its ends and provided with an elongated slot, a harmonica within the member and having its mouth fitted tightly within said slot, bifurcated passageways for feeding air to the opposite ends of the hollow member, and means located near the opposite ends for baffling the air before passing to the harmonica.

12. A unit for a player type of musical instrument comprising a hollow member sealed at its ends and provided with an elongated slot, a harmonica within the member and having its mouth tightly fitted within said slot, baffle plates within the member and located at the opposite ends of the harmonica to form small air chambers at the opposite ends of the hollow member, and means for feeding air to the said respective chambers to thereby baffle the air before passing to the said harmonica.

13. A unit for a musical instrument comprising a hollow tubular member sealed at its ends and provided with an elongated slot, a

harmonica within said tubular member and having its mouth sealed within the walls of the slot, baffle plates within the tubular member and at the opposite ends of the harmonica, a bifurcated passageway communicating with the tubular member so that the air from said bifurcated member must pass through said baffle plates before entering the harmonica, and means for holding the harmonica tightly in position.

14. A unit for a musical instrument comprising a hollow member sealed at its ends, baffle plates within the member and spaced from the ends, the hollow member provided with an elongated slot, a harmonica in the hollow member and having its mouth fitting within said slot, means for feeding air between the respective baffle plates and the ends of the hollow member, means for holding the harmonica in position, and means for sealing the mouth of the harmonica within said slot.

15. In a musical instrument of the player type, a casing having a lid, said lid and casing provided with openings to provide for the emission of sound, bell mouths also fitted to the casing for permitting the emission of sounds, a harmonica within the casing, means for feeding air to the harmonica, and means for supporting and passing a perforated music sheet over the mouth of the harmonica.

16. In a musical instrument of the player type, a casing in the form of a sound box and provided with openings for the emission of sound, a musical unit within said sound box comprising a sealed unit, said sealed unit having a harmonica therein and the mouth of the harmonica extending without the unit, passageways for feeding air to the unit, means for supporting a music roll to pass over the mouth of the harmonica, and brake means on the supporting means so that the perforated music will be held tightly against the mouth of the harmonica.

In testimony whereof we affix our signatures.

MARTIN D. ZIMMERMAN.
HARRY PULLEN.
